Primary Examiner — Mark Goodwin*(74) Attorney, Agent, or Firm* — The Webb Law Firm(57) **CLAIM**

The ornamental design for an engine hood for work machine, as shown and described.

DESCRIPTION

FIG. 1 is a front view of an engine hood for work machine showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof; and,

FIG. 8 is a rear perspective view thereof.

The portions of the engine hood for work machine shown in coarse dot pattern and outlined in dashed lines form no part of the claimed design.
